UNITED STATES PATENT OFFICE.

BERNARD FAY, OF DANBURY, CONNECTICUT.

SAFETY BLOCK SYSTEM FOR RAILROADS.

1,112,204.

Specification of Letters Patent. Patented Sept. 29, 1914.

Application filed February 27, 1913. Serial No. 751,107.

To all whom it may concern:

Be it known that I, BERNARD FAY, a citizen of the United States, residing in the city of Danbury, county of Fairfield, State of Connecticut, have invented certain new and useful Improvements in Safety Block Systems for Railroads; and I do declare the following to be a full, clear, and exact description of the invention, such as will enable others skilled in the art to which it appertains to make and use the same.

This invention relates to the subject of railway systems and the primary aim of the same is to provide simple, effective and automatic means for preventing two trains entering the same block and thereby overcome the danger of collisions.

In carrying out the objects of the invention generally stated above it is contemplated providing mechanism for each block that is actuated by the first train to enter the block to place an actuator in the path of movement of a following train so that in the event of the following train entering the block, the actuator will actuate the controlling mechanism thereof and thereby either stop or decrease the speed of the following train.

In addition to the foregoing prominent feature of the invention, the mechanism also includes means adapted to be actuated by a train leaving a block to remove the actuator from the path of movement of a train that is entering the block, so that said train freely enters the block, but immediately actuates said mechanism so that another train attempting to enter the block will either stop or have its speed materially decreased.

In producing an invention possessing the characteristics stated in the foregoing, it will be understood that the same is susceptible to changes in details and structural arrangements, a few simple and practical embodiments of which are shown in the accompanying drawings, wherein—

Figure 1 is a plan view of a portion of a railway system, divided into blocks, and each block equipped with the improved train controlling mechanism. Fig. 2 is a fragmentary side view of a motor provided with means that coöperate with the mechanism shown in Fig. 1 to control the train. Fig. 3 is a fragmentary plan view of the motor mechanism that is actuated by the track mechanism to control the speed of the motor. Fig. 4 is a plan view of two of the setting

devices and a circuit closer, the one setting device being in position to close a block and other being in position it assumed when the block is closed. Fig. 5 is a vertical sectional view of a setting device before closing a block. Fig. 6 is a view similar to Fig. 5, the setting device being in a closed position. Fig. 7 is a plan view of the circuit closer shown in Fig. 4, the same being shown in closed-circuit position. Fig. 8 is a diagrammatic view of a variation of the invention. Figs. 9, 10 and 11, are detail views showing variations of the invention.

The improved automatically operating train controlling mechanism has been shown in Fig. 1 of the drawings in connection with a railway system divided into a plurality of blocks designated generally by the characters A, B, C and D, and each block is equipped with two boxes, or protecting casings E and F, that contain the major portions of setting devices and circuit closers, respectively. The casings E and F may be disposed to one side of the rails, or in any other suitable or convenient locations.

The casings E are duplicates as well as the mechanisms they carry, and said mechanisms include a rocker shaft 12 that extends transversely through and projects well beyond the side of its casing E adjacent the rails, and adjacent its free end, the shaft carries a right angularly projecting bar 13 having a right angularly projecting end arm 14. At an intermediate point, shaft 12 carries a bar 15 which may be similar to bar 13, but is disposed at right angles to said bar 13. Within the casing E, shaft 12 is provided with a laterally projecting locking arm 16, that is in alinement with bar 13. A spring 17 connects arm 16 with the rear end of casing E and tends to normally retain arm 16 in a vertical, upright position.

To the rear of shaft 12, a rest 18 is disposed in casing E in the path of movement of an abutment 19 projecting laterally from shaft 12, said rest and abutment limiting rearward rotary movement of shaft 12 and thereby serving to prevent arm 16 moving rearwardly beyond the perpendicular. Forward of shaft 12, casing E is provided with a partition 20 that provides a chamber in which a magnet 21 is disposed. The partition 20 is provided with an opening 22 through which a spring latch 23 projects into the rocker shaft compartment. The latch 23 has an inclined cam surface that is in the path of

forward movement of arm 16 and a lip beneath which said arm "snaps" after forcing the latch through the opening 22. Latch 23 normally holds arm 16 in a forwardly projecting position, as is shown in Fig. 6 of the accompanying drawings. A rest or abutment 24 disposed beneath latch 23 limits the downward movement of arm 16. The free end of latch 23 is in the form of an armature 25 disposed adjacent to and adapted to be attracted by the magnet 21 when said magnet is energized to release the arm 16 so that spring 17 will restore said arm to its normal upright position, as will be presently explained.

The casings E as well as the mechanisms they inclose are duplicates, each comprising a rocker shaft 26 extending transversely through and projecting well beyond the casing, the free outer end of shaft 26 being equipped with a bar 27 that may be similar to and is in longitudinal alinement with the bar 13 of shaft 12. Within casing F, shaft 26 carries a contact arm 28 that is insulated from said shaft, said arm 28 being in alinement with bar 27. A spring 29 connecting arm 28 with the casing normally retains shaft 26 in position to retain arm 28 and bar 27 in upright vertical positions. Circuit terminals 30 are disposed in the path of movement of arm 28 and have circuit connections 31 with the magnet 21. By this construction it will be seen that when the circuit is closed through arm 28, terminals 30, connections 31, and magnet 21, said magnet will be energized and will attract latch 23, thereby releasing arm 16.

The motor, which may be steam operated or any other type that is equipped with a controlling lever or the like, is equipped with a pendent cam 32 which is disposed in such position that it will engage the arm of bar 13 and thereby rock shaft 12 and cause arm 16 to be caught and held by latch 23, this movement of the shaft 12 bringing bar 15 to an upright position as is shown in Fig. 4 of the drawings.

The casing E is disposed adjacent the entrance to the block and the casing F adjacent the exit therefrom, and from the preceding description it will be clear that as a train enters the block, or before it enters said block, the shaft 12 is locked in position to retain arm 15 in an upright position. The bars 13 and 27 are in longitudinal alinement, as aforesaid, so that as the train leaves the block, cam 32 engages bar 27 and rotates shaft 26 to close the circuit to magnet 21 and thereby causes the latch 23 to release arm 16.

Forward of the cam 32, the motor has a rocker shaft 33 mounted thereon provided with a crank 34 at its free end that hangs in position to engage the arm 15 when the latter is raised. In the present example of

the utility of the invention, the same has been shown in connection with a locomotive equipped with the usual throttle lever 35 and the throttle locking pawl 36. The throttle and pawl lie within a notch 37 formed in a slide bar 38 mounted in a guide 39 disposed within the cab. A lever 40 pivoted to the throttle lever has one end engaging the rear end wall of the notch 37, the other end of said lever 40 bearing against the handle of pawl 36, the arrangement being such that when slide bar 38 is moved forwardly, lever 40 first releases pawl 36 by pressure applied to the handle thereof, after which the continued movement of said bar, causes the throttle lever to move forwardly and stop or decrease the speed of the locomotive. The slide bar 38 projects beyond the cab and has a pivotal connection with a crank 41 carried by shaft 33. From the foregoing it will be clear that when crank 34 engages arm 15, shaft 33 is rotated and causes crank 41 to actuate slide bar 38 and through said slide bar and the pawl-releasing lever 40, first releases the pawl and then causes the throttle lever 35 to act upon the engine.

The relative arrangement of the setting mechanism of the preferred form of the invention is shown in Figs. 1 and 2 of the accompanying drawings, and from said figures it will be seen that before the train enters the block, cam 32 engages the actuator bar 13 and thereby rocks shaft 12 to a position where it is locked by latch 23 with bar 15 in an upright position, and said bar 15 remains in such position until released by magnet 21 when the circuit is closed by the said cam actuating the circuit closer as the train leaves the block. With this arrangement in mind, it will be clear that should a second train attempt to enter the block while the first train is therein, said second train, through the bar 15 and the described throttle-operating mechanism, would be stopped.

Variations of the invention may obviously be resorted to. For instance, as suggested in Fig. 8, two of the casings E and setting mechanisms may be included in one block so that in the event of the locomotive accidentally passing one of the setting mechanisms, it will actuate the other.

In the example shown in Fig. 9 the throttle-actuating bar may be adjustable as to height, as indicated at 15^a so that the slide bar 38 may be only actuated to a limited extent and thereby affect a partial closing of the throttle with a consequent reduction of the speed of the train.

In Figs. 10 and 11 variations of the cam 32 and the crank 34 are suggested. In the first example, the cam has been shown as being pivoted, as at 32^a, to permit the same to have a limited swinging movement; and in the second instance the crank, designated by the numeral 34^a has been shown adjust-

able. These two expedients may be resorted to as they permit the cam 32 to swing over the bar 13 and the crank 34^a to be adjusted to clear the bar 15 so that in the event of 5 the train backing, the track mechanism will not be affected.

Fig. 1 of the accompanying drawings gives a general idea of the best arrangement 10 of track mechanisms relative to the blocks, and by referring thereto it will be seen that the circuit controller for, for instance, block B controls the setting mechanism in block A, this arrangement being continued throughout the entire system. It will therefore be 15 understood that the setting mechanism in block A will be in position to decrease the speed of a train until the preceding train has entered and actuated the circuit closer in block B. Therefore, the trains will be 20 kept in spaced relation by a distance corresponding to approximately one block.

From the foregoing description it will be seen that this invention is entirely automatic in its operation and that it overcomes the 25 danger incidental to two trains occupying the same block.

What I claim as my invention is:—

1. A train controlling apparatus comprising a casing provided with a partition forming 30 a magnet chamber therein, said partition being provided with an opening, an armature in the magnet chamber and having a latching lip projecting through the opening, a shaft journaled in the casing and having 35 a projecting end portion, means carried by the projecting portion and actuated by a train for rotating the shaft, an arm carried

by the shaft within the casing and adapted to be engaged by the latching lip of the armature, a magnet in the chamber for releasing the armature from the arm, means carried by the shaft for engaging a speed controller of a train, and means actuated by a train for energizing the magnet. 40

2. A train controlling apparatus comprising 45 a casing provided with a partition forming two compartments, said partition having an opening therein, a magnet in one compartment, a spring armature mounted on the partition in the magnet compartment and provided with a lip that normally projects through the opening in the partition, a shaft journaled in the other compartment and having a portion projecting beyond the casing, an arm carried by the shaft within the casing, train actuated means carried by the projecting portion of the shaft for rotating the shaft to engage the arm with the lip of the armature, train speed controlling means carried by the shaft and placed in 55 the path of the train when the shaft is rotated to engage the arm and lip, means actuated by a train for energizing the magnet to disengage the armature and the latching arm, and means for reversely rotating the 60 shaft when the armature is disengaged from the latching arm.

In testimony whereof I affix my signature in presence of two witnesses.
